Inventor;

David Cumming Jr.

United States Patent Office.

DAVID CUMMING, JR., OF NEW YORK, N. Y.

Letters Patent No. 78,864, dated June 16, 1868.

IMPROVEMENT IN METHOD OF LOCKING NUTS.

The Schedule referred to in these Letters Patent and making part of the same.

TO ALL WHOM IT MAY CONCERN:

Be it known that I, DAVID CUMMING, Jr., of New York, county and State of New York, have invented a new and useful Improvement in Screw-Bolts; and I do hereby declare that the following is a full, clear, and exact description of the construction and operation of the same, reference being had to the annexed drawings, making a part of this specification, in which—

Figure 1 is a perspective view,

Figure 2 a longitudinal section, and

Figure 3 a transverse section.

The same letters refer to corresponding parts in the different figures.

To enable others skilled in the art to make and use my invention, I will proceed to describe its construction and operation.

A is a screw-bolt, of the usual form, in the threaded part of which I cut a key-seat, into which I insert the key C, which I make of lead or other soft metal.

The nut B, which is of the usual form, is then screwed on, the thread of the nut cutting a corresponding thread on the key. When the nut is screwed up to its place, that portion of the key X which is outside of the nut, is to be riveted up against the nut, destroying the thread on that portion of the key. The nut cannot then come off until force is used, as the nut has to cut the thread again on the key in coming back, and the key cannot get out of its seat until the nut is taken off, thereby preventing the nut from being shaken off as is frequently the case where screw-bolts are used in the construction of railroad-cars, carriages, bridges, and other structures.

I do not confine myself to the use of lead, as any soft metal, material, or composition can be used for making the keys.

I am aware that nuts have been prevented from turning by means of a key, of iron or other hard metal, inserted in a key-seat, cut in the threaded part of the bolt; but this I do not claim.

What I do claim, and desire to secure by Letters Patent, is—

The key, of lead or other similar soft metal, when constructed and applied substantially as herein described and for the purpose set forth.

Witnesses:

WILLIAM S. PRICE,

CHARLES METTNER.

DAVID CUMMING, JR.
